COMPRESSOR

Paul Kellsman, New York, N. Y.

Application August 28, 1944, Serial No. 551,511

10 Claims. (Cl. 230—79)

1

This invention relates to a rotary, liquid piston machine, and more particularly to a rotary compressor using a liquid as a compressing medium.

The structural features of the machine herein disclosed, other than the mounting of the external rotor, are described and claimed in my co-pending application Serial No. 551,509, entitled Compressor, filed August 28, 1944.

One object of the invention lies in an improved mounting for the external rotor of a rotary machine using a liquid as a compressing medium.

Another object of the invention is the provision of a rotary compressor or other machine using a liquid as a compressing medium and having internal and external eccentrically mounted rotors in which the external rotor is so mounted as to permit variation in the amount of eccentricity.

Another object of the invention is the provision of a rotary compressor or other machine using a liquid as a compressing medium and having internal and external eccentrically mounted rotors in which the external rotor is resiliently mounted to vary the eccentricity in accordance with the compressor outlet pressure.

Other objects and features of the invention will be readily apparent to those skilled in the art from the specification and appended drawing illustrating certain preferred embodiments in which:

Figure 1 is a longitudinal vertical sectional view of a compressor according to the present invention.

Figure 2 is a diagrammatic view of one form of rotor mounting according to the present invention.

Figure 3 is a schematic view of another form of rotor mounted according to the present invention.

The compressor, as specifically illustrated, comprises a bed plate 1 on which are mounted supports 2 and 3. Within the support 2 is mounted a stationary structure 4 containing the compressor outlet 5 and intake and outlet chambers 6 and 7. Within a roller bearing 8 in the interior end of the stationary structure 4 and a roller bearing 9 in the support 3 is rotatably mounted a drive shaft 11 carrying an inner rotor 12 having a pair of spaced peripheral annular plates 13 mounted thereof between which extends separator plate 16 dividing the peripheral space between the plate 15 into a large number of individual pockets. Each of these pockets has an opening 17 in its base communicating in the proper position with the inlet port 18 in the wall

2

of the chamber 6 and with the outlet port 19 in the wall of the outlet chamber 7.

Exteriorly of the rotor 12 is eccentrically supported the outer rotor indicated at 21 and comprising spaced annular plates 22 and 23 connected by the cylindrical portion 24. On the plates 22 and 23 are mounted annuli 25 and 26 forming wells 27 and 28 within which liquid escaping from the interior of the compressor adjacent the outlet is trapped and maintained by centrifugal force to be returned to the compressor adjacent the inlet portion thereof. A liquid supply source is indicated at 29. The rotor 21 as shown in Figures 1 and 2 is rotatably supported in its position eccentric to the axis of shaft 11 by means of an endless belt or strap 31 which engages the periphery of the cylinder 24 between the external ends of the plates 22 and 23. The belt 31 extends over an idler pulley 32 supported by bearing 33 upon an arm 34 pivoted at 35 to a fixed part. The opposite end of the arm 34 is connected to the operating piston of a pneumatic cylinder 36, the cylinder being connected in one concept of the invention to the compressor outlet 5 through constant pressure outlet valve 37.

By mechanically supporting the rotor 21 by the belt 31, it is possible to mount a relatively large diameter rotor with a relatively small and inexpensive bearing 33. The direct support of this exterior roller about the other elements of the compressor ordinarily results in a complicated and expensive bearing arrangement while with the suspension herein disclosed a small and economical bearing may be employed.

Another feature of the invention lies in the automatic regulation of the output pressure of the compressor. The outlet of the constant pressure outlet valve 37 results in a constant force tending to raise the rotor 21. If the outlet pressure of the compressor should increase, the reaction force on the rotor tending to move it toward concentricity will be increased and the rotor will move downwardly from the positions of Figures 1 and 2 into a less eccentric position. This decrease in eccentricity decreases the travel of the liquid into the compression chambers of the inner rotor and lowers the output pressure. Since the force tending to move the rotor upwardly is constant, the reaction force thereagainst will be maintained constant and accordingly there is an automatic regulation of the output pressure.

In the modification of Figure 3 there has been substituted for the belt 31 a pair of spaced rollers 38 and 39 mounted on a yoke 41 carried by the

operating piston of a pneumatic cylinder 42. This construction again provides for the mechanical supporting of the exterior rotor with relatively small and inexpensive bearing elements and also provides the automatic regulation of the compressor output pressure in the same manner as the embodiment of the invention illustrated in Figures 1 and 2.

While the invention has been specifically illustrated in connection with a gas compressor, it will, of course, be obvious that various features thereof are applicable to engines and other forms of liquid piston machinery and, while certain preferred embodiments of the invention have been specifically disclosed, it is understood that the invention is not limited thereto as many variations will be readily apparent to those skilled in the art and the invention is to be given its broadest possible interpretation within the terms of the following claims:

What is claimed is:

1. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, and means for mechanically supporting said exterior rotor in its eccentric position and having rolling engagement with the exterior periphery of said rotor.

2. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, means for mechanically supporting said exterior rotor in its eccentric position and having rolling engagement with the exterior periphery of said rotor, and means for adjusting said support to vary the eccentricity between the rotors.

3. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, means for mechanically supporting said exterior rotor in its eccentric position and having rolling engagement with the exterior periphery thereof, and means supplying a constant biasing force to said support by which it floatingly holds said exterior rotor in its eccentric position whereby a constant pressure for the machine is obtained.

4. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, and means supporting said exterior rotor adjustable to vary the eccentricity between the rotors.

5. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, means floatingly supporting said exterior rotor in its eccentric position, and means supplying substantially a constant bias to said supporting means whereby a constant pressure for the machine is automatically attained.

6. In a gas compressor, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, a continuous belt engaging the outer periphery of said exterior rotor, and an idler pulley engaging and supporting said belt whereby the exterior rotor is supported in its eccentric position.

7. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, a continuous belt engaging the outer periphery of said exterior rotor, an idler pulley engaging and supporting said belt whereby the exterior rotor is supported in its eccentric position, and means for varying the position of said idler roller to vary the eccentricity between the axes of said rotors.

8. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, a continuous belt engaging the outer periphery of said exterior rotor, an idler pulley engaging and supporting said belt whereby the exterior rotor is supported in its eccentric position, and means floatingly supporting said idler roller with a constant bias whereby the eccentricity of the rotor axes will be automatically varied to maintain a substantially constant pressure for the machine.

9. In a rotary, liquid piston machine, an exterior rotor having an annular portion for the reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rotors to effect rotation thereof, and a plurality of rollers engaged by the periphery of said exterior rotor to maintain it in eccentric position.

10. In a rotary, liquid piston machine, an exterior rotor having an annular portion for the

reception of a compressing liquid, a compressing liquid in said portion, an interior rotor in said portion mounted on an axis eccentric to the axis of said exterior rotor and having a plurality of open chambers about the periphery thereof, gas inlet and outlet ports for said chambers, means for driving said rollers to effect rotation thereof, a plurality of rollers engaged by the periphery of said exterior rotor to maintain it in eccentric position, and means floatingly supporting said rollers under a constant bias whereby the eccentricity of the rotors will be automatically varied

to maintain a substantially constant pressure for the machine.
